(57) **CLAIM**

The ornamental design for a handle and top structure for
condiment storage and dispensing carousel, as shown and
described.

DESCRIPTION

FIG. 1 is a perspective view of a first embodiment of the
handle and top structure, the bottom surface of which is
unadorned;

FIG. 2 is a left side elevation view of the handle and top
structure of FIG. 1;

FIG. 3 is a left side elevation view of the handle and top
structure shown in FIGS. 1 and 2;

FIG. 4 is a perspective view of another embodiment of the
handle and top structure;

FIG. 5 is a left side elevation view of the handle and top
structure of FIG. 4; and,

FIG. 6 is a front elevation view of the handle and top structure
of FIGS. 4 and 5.
